UNITED STATES PATENT OFFICE

IRA G. DAVIS, OF SOUTH TAMWORTH, NEW HAMPSHIRE, ASSIGNOR TO SOUTH TAMWORTH INDUSTRIES, INC., OF SOUTH TAMWORTH, NEW HAMPSHIRE, A CORPORATION OF NEW HAMPSHIRE

DESIGN FOR A KNOCKER

Application filed August 1, 1930. Serial No. 36,531. Term of patent 7 years.

To all whom it may concern:

Be it known that I, IRA G. DAVIS, a citizen of the United States of America, residing in South Tamworth, in the county of Carroll and State of New Hampshire, have invented a new, original, and ornamental Design for a Knocker, of which the following is a specification, reference being had to the accompanying drawing, forming part thereof.

Figure 1 is a side elevation of a knocker showing my new design. Figure 2 is a front elevation of the knocker.

The design consists of a caricature figure

of an animal simulating a bird which is adapted to be mounted upon a door. The novelty of the design consists in the caricaturistic outline accentuated by caricaturistic ornamentation about the head and wings thereof.

I claim:

The ornamental design for a knocker or similar article as shown and described.

Signed by me at South Tamworth in the county of Carroll and State of New Hampshire, this 28th day of July, 1930.

IRA G. DAVIS.
